(57) **CLAIM**

The ornamental design for a golf bag, as shown and described.

DESCRIPTION

FIG. 1 is a perspective view of the golf bag of this invention; FIG. 2 is a front view of the golf bag of this invention; FIG. 3 is a first side view of the golf bag of this invention; FIG. 4 is a rear view of the golf bag of this invention; FIG. 5 is a second side view of the golf bag of this invention; FIG. 6 is a top plan view of the golf bag of this invention; and,

FIG. 7 is a bottom plan view of the golf bag of this invention. In FIGS. 1-7, the broken-lines representing the top cuff of the golf bag, the plate near the top of the rear side, and the word "Titleist" on the right and left sides and bottom surface form no part of the claimed design. The heavier dash-lines disclosed on the golf bag represent conventional stitching.
